CLAIM

The ornamental design for a handleset escutcheon, as shown and described.

DESCRIPTION

FIG. 1 is a perspective view of handleset escutcheon showing my new design;

FIG. 2 is a front view of the new design for an escutcheon; FIG. 3 is a top view of the new design for an escutcheon, the bottom view being the mirror image;

FIG. 4 is a right side view of the new design for an escutcheon, the left side view being a mirror image;

FIG. 5 is a back view of the new design for an escutcheon.

FIG. 6 is a perspective view of a second embodiment of a handleset escutcheon showing my new design; and, FIG. 7 is a front elevational view thereof, the top, bottom, and side views are the same as FIG. 1.

The broken lines in the Figures are for illustrative purposes only and form no part of the claimed design.
